STRIP ROLL SEALING MACHINE

Eugene M. Kile, Akron, Ohio, and Simon Kain,
Chicago, Ill., assignors to John E. Fast & Co.,
Chicago, Ill., a corporation of Illinois

Application September 18, 1944, Serial No. 554,606

7 Claims. (Cl. 270—27)

The machine of the present invention constitutes an improvement in certain particulars of the machine set forth and described in Letters Patent No. 2,205,171, issued June 18, 1940, and in its general character the present machine closely follows that of the patent referred to.

The machine illustrated makes provision for the winding of condensers from webs of metal foil and paper which are fed in superposed relation from spools so arranged as to feed to a common line of advance, so that a laminated composite strand of foil and paper will be delivered to a mandrel upon which the condenser will be wound until it is built up to the desired dimensions, at which time the strips of foil and paper will be automatically and successively severed so that the terminus of the foil will lie within the final paper windings and be thoroughly protected thereby. The strips of foil may be slightly staggered with respect to the paper strips, so that the edges of the respective foil strips will be oppositely protruded or exposed at the ends of the condenser and in position to have the heads of wire soldered thereto.

The present invention is directed more particularly to the means provided for feeding forwardly a binder strip which is wound around the completed condenser to prevent the unwinding of the same. In the patented construction provision was made for adhering the terminus of the outermost paper winding directly to the body of the wound condenser, but experience has shown that the stiffness due to the number and heavier character of the paper strips precluded the satisfactory use of certain glues or similar adherent materials and that better results were obtained by introducing the leading end of a short section of paper strip into the terminal windings of the condenser so that its exposed end would extend more than one full turn beyond the end of the paper with the result that when glue is applied, the paper strip will adhere to itself. The present invention makes provision for the feeding and adhering of such a binder strip to a wound condenser or other wound-up roll of strip material. Further objects and details will appear from the description of the invention in conjunction with the accompanying drawings, wherein:

Figure 1 is a side elevation of a winding machine embodying the features of the present invention;

Fig. 2 is a detail of the feeding and moistening mechanism for the binder strip;

Fig. 3 is an enlarged sectional detail of the feeding and moistening mechanism including the

knife for severing the binder strip and the paper windings of the condenser;

Fig. 4 is a detail taken on line 4—4 of Fig. 3 looking in the direction of the arrows and showing the feeding connections for the binder strip;

Fig. 5 is a fragmental elevation of the binder strip feeding mechanism shown in Fig. 2;

Fig. 6 is an end view of the same;

Fig. 7 is a detail taken on line 7—7 of Fig. 3;

Fig. 8 is a perspective view of the binder strip being applied to the paper windings of the condenser; and

Fig. 9 is a similar view showing the binder strip sealed around the completed condenser.

15 The frame and mountings for the operating parts are substantially identical with those shown in the patent referred to, and comprise a table 20 supported on suitable end standards 21 and carrying a vertically extending upper frame or superstructure 22 which affords a mounting for a series of drums 23 carrying rolls of suitable insulating paper P, P¹, P², and P³, four being shown in the present embodiment, although a greater or lesser number might be employed. The upper 20 frame also serves as a mounting for a pair of rolls of a suitable foil F, two of said rolls being shown in the present embodiment.

As shown, the rolls of metal foil on each side occupy an intermediate position with respect to the paper rolls, so that, in the feeding of the composite strand from which the condenser is built up, there will be six layers or laminations, two paper layers occupying the center position with single layers of foil on each side thereof, and with single layers of paper occupying the outermost positions. However, as the composite strand is wound upon itself, the single outer layers of successive convolutions will overlie one another, so that in the completed condenser each strip of foil will be separated by two strips of paper. The edges of the respective strips of foil may be offset slightly oppositely with respect to the adjacent edges of the paper strips, so that the foil in the completed condenser will be exposed at each end, although the respective foil strips throughout all portions of the condenser are separated from one another.

The paper and foil strips are fed downwardly over guide rolls 24 to be united into a strand 50 which is wound upon a divided mandrel 25 of the character described in the patent aforesaid, and it is not here deemed necessary to describe in detail the construction of the mandrel. The foil strips are fed from rolls F which are carried by spools 26 of the character shown in the patent,

and are restrained from overrunning by friction bands 21, which likewise need not be described in detail.

Provision is made for puncturing the foil strips by the passage of electric sparks discharged from needle points 28 and associated mechanism of the character shown in the patent referred to, the current being charged into condensers 29 in the manner shown in said patent. Provision is also made for the discharge of the sparks which perforate the foil in advance of the severing of the paper strips by a knife blade 30, so that the paper strips will overlie and enclose the foil, but these features are fully set forth in the patent referred to, the cam 30a corresponding to the cam 192 of the patent for actuating connections of the character therein shown to time the knife stroke.

The binder strip B, shown in Figs. 8 and 9, is fed from a spool 31 (Fig. 2) mounted below the table 20 and carried upwardly through an aperture 32 and around an elbow-shaped guide member 33 provided on its rounded outer surface with a channel 34 for the reception of the strip, the forward end of which is entered within a channel 35 in an upper guide block 36 which cooperates with a lower guide block 37 in providing a closed passage-way for the strip, so that the leading end thereof will be projected outwardly toward the mandrel and at a proper angle of elevation above the mandrel to bring the leading end of the strip into contact with the terminal portion of the advancing strand, with the result that the leading end of the binding strip will be caught within the bite of the terminal convolutions being applied to the condenser and wound up therewith to carry the binding strip around the completed condenser, as shown in Fig. 9.

The leading section of the binder strip is cut free from the remainder of the strip through the action of a spring cutter 38, the downturned free end 39 of which terminates in a serrated cutting edge 40 (Fig. 7), which moves within a slot 41 in the upper guide block 36 and in register with a cross slot 42 in the lower guide block 37 across which the binder strip is carried. The opposite end 43 of the spring cutter is downturned and bolted to the upper guide block, the arrangement being such as to permit the free cutting end of the spring cutter to be forced downwardly to sever the binder strip at the proper time. The severing of the binder strip is effected by the forward advance of the knife blade 30, which is positioned to strike through the composite strand of paper and foil at a point slightly behind the line of contact of the leading end of the binder strip, so that the terminus of the strand will be drawn down and folded around the end of the binder strip and both be wound up together.

In order to actuate the cutter 38 by the forward advance of the knife, the knife is provided with a rounded boss 44 which is positioned to engage a rounded hump 45 at the bend of the spring cutter, so that, as the knife advances, the cutter will be depressed at the proper instant to permit the binder strip to be caught within the last convolution of the strand and drawn forward. As the binder strip is being wound up, it will be contacted by the upward thrust of a glue swab 45a which applies a spot of glue to the binder strip before it is completely wound, so that the outermost turn of the strip will be sealed by a gluing device identical with that disclosed in the patent aforesaid actuated by cam 45b corresponding to cam 215 and connections therein shown.

The means provided for operating and timing

the knife, and for lifting, rotating, timing and actuating the mandrel, and for removing the completed condenser therefrom, are all set forth in detail in the patent referred to.

5 The binder strip is drawn upwardly from the spool 31 through the contact of a beveled friction roller 46, which presses the strip upwardly against an overhanging lip 47 rearwardly extending from the upper guide block 36 and serves to shove forward the confined leading section of the strip. The roller 46 is mounted upon the end of a shaft 48, which extends through the wall of the upper frame 22 and is suitably journaled therein.

10 The shaft 48 has pinned thereon a rabbeted drum 49 provided with ratchet teeth 50, which are adapted to be engaged by a spring pressed dog 51 carried by the flanged end 52 of a drum 53 freely mounted upon the shaft 48. The opposite face of the ratchet drum 49 bears against a friction ring 54 which is interposed between the ratchet drum and a plate 55, which is slidably mounted upon supporting rods 56 or the like outwardly extending from the upper frame. The end 57 of the shaft 48 is threaded to receive a thumb nut 58, which bears against the interposed spring 59, which applies pressure to the plate 55 to hold the friction disk in compressive relation against the outer face of the drum 49.

15 The drum 53 has wound thereon the upper terminus of an operating cable 60, and also has 20 reversely wound thereon the upper terminus of a restoring cable 61 connected with a spring 62. The operating cable (Fig. 2) is carried downwardly around a pulley 63 carried by a lever 64 pivoted at its opposite end on a pivot rod 65 and carrying at an intermediate point a contact roller 66 which engages the edge of a cam 67 mounted upon a cam shaft 68 which corresponds to the cam shaft 75 of the patent referred to, which cam shaft carries the cams for operating the mandrel and knife, as described in detail in the aforesaid patent.

25 The cable 60, after passing around the pulley 63, is carried upward around a pulley 69, and 30 thence downwardly to an eye 70 at the outer or free end of the lever 64, so that, as the lever is depressed by the high point on the cam, the upper end of the cable 60 will be drawn downwardly, thereby unwinding the cable convolutions on the 35 drum 53, which acts through the dog 51 and ratchet to impart rotation to the shaft 48 and roller 46. At the same time the oppositely wound restoring cable will be wound up under spring tension, so that, when the lever roller 66 is released from the high point on the cam, the restoring cable will act to draw back the spring dog 51 around the ratchet drum, without, however, imparting reverse rotation thereto. This serves to feed forward the desired length of wrapper strip for severance as the knife 30 advances to 40 cut off the leading section in preparation for the next succeeding feeding movement of the roller 46.

45 In view of the fact that it is necessary to provide for the adjustment of the guide blocks 36—37 in order to feed the binding strip to condensers of varying diameter, the guide blocks are mounted within a bifurcated yoke 71, the prongs of which 50 embrace the upper and lower guide blocks, as shown in Fig. 5. The yoke is carried by a stub shaft 72 entered through a bearing 73 and provided on its end with a finger 74 which is split at its lower end 75 to embrace the end of the shaft 72 upon which it is clamped by the tightening 55 of a screw 76. The upper end of the finger

is engaged by a coil spring 77 and is provided with an adjusting screw 78 bearing against an abutment 79, which permits the shaft 72 to be rocked slightly to afford necessary angular adjustment to the feeding blocks to direct the strip to the desired position to engage the terminal portion of the downwardly traveling strand of material.

In order to cause a rupture of the strips of foil after the same have been pierced by the electric sparks from the needles 28, provision is made for applying braking pressure to the spools which carry the foil, through the medium of a cable 30, the action of which is controlled by a photoelectric cell 81 which coacts with a source of illumination 82, so that, as the line of perforations in the foil pass through the line of light transmission from the source to the cell, a beam will be transmitted to the cell which controls the setting of the brakes on the spools, thereby rupturing the foil in the manner described in the patent previously referred to.

Provision is also made for raising and lowering the mandrel and associated mechanisms, but all of these features are identical with the disclosures of said patent.

Operation

The rolls of paper and foil are mounted upon the respective spools, and the paper spools are adjusted to stagger the paper strips with respect to the foil strips, so that one edge of one of the foil strips will protrude from one side of the paper while the opposite edge lies within the opposite margins of the paper, the companion foil strip being similarly arranged to protrude beyond the opposite edges of the paper strips.

After accurate adjustment has been made to feed the paper and foil strips in proper relation, the mandrel will be lifted to engage the leading end of the composite strand, after which power is applied to begin the winding operation.

At a timed period in the feeding operation, the sparks emitted from the needle point 28 will puncture through the foil strips to provide a weakened line of severance, and thereafter the application of a braking pressure on the foil spools will prevent additional feeding and cause the rupturing of the foil strips prior to the advance of the knife 30, which severs the paper and completes the cutting free of the composite strand.

Prior to the advance of the knife, however, the leading end of the binder strip will be thrust inwardly by the action of the feed roller 46 so that the binder strip will be caught within the convolutions of the strand and a proper length thereof cut off and wound around the terminus of the paper strand to the extent necessary to cause the strip to be sealed upon itself by the application of a glue spot, so that unwinding and disintegration of the completed condenser will be prevented; after which the completed and sealed condenser will be discharged from the mandrel.

The throw of the lever 64, which is regulated by the cam 67, will determine the extent of the feeding thrust imparted to the strip by the roll 46 so that a proper length of the binder strip will be advanced and severed in preparation for the final sealing of the strip around the condenser.

The device is one which assures speed and accuracy in the performance of the operations required in sealing the wound up condenser and enables the employment of a sealing strip of the character best fitted for the purpose, irrespective

of the nature of the materials employed as constituents in the condenser itself.

Although the machine has heretofore been described as one which is particularly adapted to the winding and sealing of rolled-up condensers, it is not the intention to limit the employment of the strip sealing features to machines employed exclusively in the winding of condensers, since the sealing features may be employed in the binding and sealing of a roll of strip material irrespective of the nature of the strips or the use for which the roll is intended.

We claim:

1. In a machine of the class described, means for drawing forward and winding up strip material into the form of a compact roll, means for holding a binding strip adapted to encircle and seal the roll, a guide for the forward end of the binding strip located in proximate relation to the point where the strip material merges into the wound up roll, a feeding roll adapted to bear against the binding strip and thrust the forward end thereof into the bite of the strip material being wound up, a cutter for severing the advanced end of the binding strip, means for adhering the severed section of the binding strip as it is wound around the roll of material, a shaft upon which the feeding roll is mounted, a drum freely mounted upon said shaft, a ratchet member fixedly mounted upon said shaft, a dog carried by the freely mounted drum and engaging said ratchet member, a winding cable having its end wound around the drum, a restoring cable having its end reversely wound around the drum, means for exerting a tension on the restoring cable, and means for drawing down the winding cable to impart feeding rotation through the dog and ratchet to the roller-shaft.
2. In a machine of the class described, means for drawing forward and winding up strip material into the form of a compact roll, means for holding a binding strip adapted to encircle and seal the roll, a guide for the forward end of the binding strip located in proximate relation to the point where the strip material merges into the wound up roll, a feeding roll adapted to bear against the binding strip and thrust the forward end thereof into the bite of the strip material being wound up, a cutter for severing the advanced end of the binding strip, means for adhering the severed section of the binding strip as it is wound around the roll of material, a shaft upon which the roller is mounted, a drum freely mounted upon said shaft, dog and ratchet mechanism for imparting rotation from the drum to the shaft when the drum is rotated in a feeding direction, a feeding cable having its end wound around the drum, a tensioned restoring cable having its end reversely wound around the drum, and means for drawing down the feeding cable to impart feeding rotation to the drum against the tension of the reversely wound restoring cable.
3. In a machine of the class described, means for drawing forward and winding up strip material into the form of a compact roll, means for holding a binding strip adapted to encircle and seal the roll, a guide for the forward end of the binding strip located in proximate relation to the point where the strip material merges into the wound up roll, a feeding roll adapted to bear against the binding strip and thrust the forward end thereof into the bite of the strip material being wound up, a cutter for severing the ad-

vanced end of the binding strip, means for adhering the severed section of the binding strip as it is wound around the roll of material, a shaft upon which the feeding roll is mounted, a drum freely mounted upon said shaft, a ratchet member fixedly mounted upon said shaft, a dog carried by the freely mounted drum and engaging said ratchet member, a winding cable having its end wound around the drum, a restoring cable having its end reversely wound around the drum, means for exerting a tension on the restoring cable, means for drawing down the winding cable to impart feeding rotation through the dog and ratchet to the roller shaft, a friction member bearing against the ratchet, and means for adjusting the frictional pressure exerted thereby.

4. In a machine of the class described, means for drawing forward and winding up strip material into the form of a compact roll, means for holding a binding strip adapted to encircle and seal the roll, a guide for the forward end of the binding strip located in proximate relation to the point where the strip material merges into the wound up roll, a feeding roll adapted to bear against the binding strip and thrust the forward end thereof into the bite of the strip material being wound up, a cutter for severing the advanced end of the binding strip, means for adhering the severed section of the binding strip as it is wound around the roll of material, a shaft upon which the feeding roll is mounted, a drum freely mounted upon said shaft, a dog carried by the freely mounted drum and engaging said ratchet member, a winding cable having its end wound around the drum, a restoring cable having its end reversely wound around the drum, means for exerting a tension on the restoring cable, means for drawing down the winding cable to impart feeding rotation through the dog and ratchet to the roller shaft, a frictional disk bearing against the ratchet, an adjustably mounted plate bearing against the friction disk, a thumb nut threaded on to the end of the roller shaft, and a spring interposed between the thumb nut and the plate and adapted to have its pressure varied by adjustment of the thumb nut.

5. In a machine of the class described, means for drawing forward and winding up strip material into the form of a compact roll, means for holding a binding strip adapted to encircle and seal the roll, a guide for the forward end of the binding strip located in proximate relation to the point where the strip material merges into the wound up roll, a feeding roll adapted to bear against the binding strip and thrust the forward end thereof into the bite of the strip material being wound up, a cutter for severing the advanced end of the binding strip, means for adhering the severed section of the binding strip as it is wound around the roll of material, a shaft upon which the feeding roll is mounted, a drum freely mounted upon said shaft, a ratchet member fixedly mounted upon said shaft, a dog carried by the freely mounted drum and engaging said ratchet member, a winding cable having its

end wound around the drum, a restoring cable having its end reversely wound around the drum, means for drawing down the winding cable to impart feeding rotation through the dog and ratchet to the roller shaft, a frictional disk bearing against the ratchet, an adjustably mounted plate bearing against the friction disk, a thumb nut threaded onto the end of the roller shaft, a spring interposed between the thumb nut and the plate and adapted to have its pressure varied by adjustment of the thumb nut, timed automatic means for drawing down the feeding cable, and timed automatic means for actuating the binder strip cutter.

15 6. In a machine of the class described, the combination of means for drawing forward and winding up strip material into the form of a compact roll, a knife for severing the strip material in advance of the completion of the roll, a guide for a binding strip positioned to direct the leading end of the strip to a point where it will be caught and wound up with the terminal convolutions of the strip material, a mounting for the guide and means for adjusting the angularity of said guide to direct the binder strip to the desired point with relation to the wound up roll, a feeding roll contacting the binder strip, timed means for actuating said roll to advance the feeding strip, a spring cutter secured at one end to the guide and having its opposite free end downturned to afford a cutting edge adapted to sever the binder strip when depressed, means carried by the knife and adapted when the knife is advanced to engage and depress the cutter to cut off a section of the binder strip after the same has been drawn into the bite of the roll being wound, a swab mounted to be brought into contact with the binder strip being wound around the roll for adhering the same, and timed automatic means for actuating said swab.

20 7. In a machine of the class described, the combination of means for drawing forward and winding up strip material into the form of a compact roll, a knife for severing the strip material in advance of the completion of the roll, a guide for a binding strip positioned to direct the leading end of the strip to a point where it will be caught and wound up with the terminal convolutions of the strip material, a mounting for the 25 guide and means for adjusting the angularity of said guide to direct the binder strip to the desired point with relation to the wound up roll, a feeding roll contacting the binder strip, timed means for actuating said roll to advance the feeding strip, and a cutter in the form of a spring plate having one end rigidly secured to the guide and having its opposite end downturned and terminating in a cutting edge having at its bend an upstanding portion adapted to be engaged 30 by a protruding portion of the knife when advanced to cut off a section of the binder strip after the same has been drawn into the bite of the roll being wound.
